UNITED STATES PATENT OFFICE.

ADOLPH PRINCE, OF CHICAGO, ILLINOIS.

BUTTER-PRESS AND STAMPING-MACHINE.

No. 851,484.

Specification of Letters Patent.

Patented April 23, 1907.

Application filed August 6, 1906. Serial No. 329,479.

To all whom it may concern:

Be it known that I, ADOLPH PRINCE, a citizen of the United States, residing at Chicago, in the county of Cook and State of Illinois, have invented a new and useful Improvement in a Butter-Press and Stamping-Machine, of which the following is a specification.

This invention relates to a device for stamping and printing butter pats and the object of the invention is a device of this kind which will be very simple in construction and by means of which a number of butter pats may be pressed in a mould and printed at one time.

The invention consists of the novel features hereinafter described, pointed out in the claims and shown in the accompanying drawings, in which,

20 Figure 1 is a perspective view of my device. Fig. 2 is a longitudinal section.

In these drawings A represents a suitable base upon which is arranged two parallel guide bars B. A frame C is carried by these bars and comprises two vertical standards C', which extend above the frame at a point midway its ends and are connected at their upper ends by a cross piece C². A lever D, is pivoted at one end to an end of the frame 30 C and extends between the standards C'.

A presser board D' is adapted to move vertically in the frame C and carries a central post D² which is connected by a coil spring D³ to the cross piece C², the lever D passing loosely between the spring and the upper end of the post D², and bearing upon the said upper end of the post.

A scraper E, is carried by the front end of

the frame C. A board F' serves as a mould base and is adapted to slide between the 40 guides B. A mould consisting of sides F² and partitions F⁴ rests upon the base F' and is locked to the same by hooks F³ which engage suitable eyes carried by the base F'.

In operation the butter is placed in the 45 compartments of the mould and the base F' is moved along the base board A, between the guides B into position beneath the presser board D' which may have any suitable stamp formed upon its under face, and the lever D 50 is depressed forcing the presser board upon the butter and packing it solidly in the compartments of the mould.

The scraper E removes any surplus amount of the butter so that it will pass readily into 55 position under the presser board. The presser board is braced by means of suitable brace guards D⁴.

Having thus fully described my invention, what I claim as new and desire to secure by 60 Letters Patent, is:—

A device of the kind described comprising parallel guide bars, a frame carried thereby, a presser board movable vertically in the frame, a post carried by the presser board, 65 a lever pivoted at one end to the frame and bearing upon said post, a mould base slidable between the guide bars, a mould carried by said base, and a scraper arranged at the front end of the frame as and for the purpose set 70 forth.

ADOLPH PRINCE.
